GAME

Clarence A. Watkins, Forest Hills, N. Y.

Application September 22, 1938, Serial No. 231,118

5 Claims. (Cl. 273—108)

This invention relates to an improved game apparatus, and relates more specifically to a novel game of skill which is capable of being played by two or more persons.

5 One of the principal objects of the present invention is the provision of a game apparatus comprising a board, preferably having a geographical area marked thereon, and various points of interest in such area being suitably marked by 10 numerical designations.

The game may be played either with moving pieces which are moved progressively over the area, or it may be played by means of placing 15 movable pieces having numerical designations thereon which are equivalent to the numbers of the geographical areas which the players remove from the playing board as the game progresses. Movement of the pieces or removal thereof from the board is controlled by means of a novel 20 indicating device, which is actuated by the individual players and which requires a high order of skill in order to secure the desired result.

This portion of the game includes a rotating or traveling member which is mounted on a horizontal 25 and slightly inclined rail, the rail being mounted on a base member which may be moved to a position which is convenient for each successive player. Adjacent to one end of the base member there are positioned a plurality of spaced 30 graduations and the effort of the player is to set the rotating or traveling member in motion and endeavor to cause same to stop opposite one of the more favorable graduations. The rotating member is so constructed as to require a relatively 35 high order of skill on the part of the player in order to make appreciable progress in the playing of the game.

Another object of the invention is the provision 40 of a novel game apparatus provided with a manually actuated traveling member which is successively operated by the individual players for enabling such players to build up their scores in the game, such apparatus being capable of use in a variety of games of skill as well as the games described herein.

45 In the drawing:

Fig. 1 is a plan view of the playing board with the inclined rail position thereon;

Fig. 2 is a side elevation of the inclined rail with 50 the traveling member in starting position;

Fig. 3 shows a detailed view of the traveling member; and

Fig. 4 is a plan view of one of the movable pieces.

55 Referring now more specifically to the drawing,

Fig. 1 illustrates the playing board which is provided with a map 10 having representations of any suitable kind thereon, the map illustrated in the drawing being a representation of the geographical area within the vicinity of the New York World's Fair. It is to be understood, of course, that the invention is not to be limited to any specific representation of this character. On this map various geographical areas 9 are indicated, each of such areas having therein a numerical designation.

A plan view of the novel device for building scores is illustrated in Fig. 1 and is designated generally by the reference numeral 11. This device is movable about the playing board and includes an elongated base member 13 having upright supports 15 and 16 at opposite ends thereof upon which are mounted the terminals of a rail 17, the rotatable or traveling member 12 being mounted on said rail.

In order to facilitate the movement of the traveling member 12, the rail is slightly downwardly inclined from the starting position of the member, as illustrated in Fig. 2. On the upper surface of the rail 17 there is formed a plurality of 25 spaced concave recesses 20 which have a slight deterrent action to the member 12 as it rolls along the rail, and when the member finally comes to rest it resides in one of such recesses. Below each of these recesses a numeral 14 indicating the 30 score obtained by each play is positioned, transverse lines 14' separating the numerals.

A more detailed view of the traveling member is shown in Fig. 3. Mounted upon a shaft 22 are two metal discs 23 and 24 of substantial thickness, each of which is fixed in position either by a drive fit or a set screw arrangement. One end of the shaft extends some distance beyond the disc 23 and on its extremity is mounted a knurled knob 25 to be grasped by the fingers and spun 40 around to give propelling force to the device. Between the two wheels is mounted a hub 21 concentric with the shaft but free to turn upon it. At the ends of the hub 21 are flanges 26 and 27 which keep the device aligned with the rail 17 and 45 also provide friction with the side faces of the discs 23 and 24 which communicate power to the hub and causes it to move along the rail.

As previously stated, the present game may be played in a variety of ways, one of which is to 50 have the players place the movable pieces upon the numerically indicated areas and successively move such pieces from place to place in numerical order until one player has reached the finish. These movable pieces may take any conven- 55

tional form, the disk 30 illustrated in Fig. 4 and having a numerical designation thereon being one of such forms.

In the embodiment illustrated, the numbers 5 run from 1 to 9 and then to 25 and each player places his movable piece upon one of the areas marked "1" at the start of the game. The traveling member and support are then moved on the playing board to a position convenient to the first 10 player who spins the traveling member, the object being to obtain 25 points before moving his chip to the next successive area. In the event that such player causes the traveling member to stop adjacent to the area marked "25" on the 15 base 13 in the first spin, he then moves his piece.

In the event, however, that he obtains a lesser number of points in the first spin, he is permitted a second spin, and then in the event that he has not obtained 25, he passes the traveling 20 member to the next player and retains his score for the next play. If, however, on such next play he obtains a score in excess of 25, he may nevertheless move his piece and retain the balance above 25 for his next play. The traveling member is thus moved from player to player, each 25 player having two spins, and the first player moving his piece from 1 through 9 and then to 25 is the winner of the game.

When played in this fashion only as many 30 movable pieces are employed as there are players in the game, and each player identifies his movable piece by the number thereon. In the event, however, that the game is to be played by removing pieces from the board, a plurality of 35 pieces having similar numerical designations thereon are placed upon each of the areas numbered from 1 to 9 and 25, and each player is given one spin of the traveling member. When the traveling member comes to rest, the disk 40 corresponding to the number on the base member 13 is removed by the player, and as soon as all of the pieces have been removed from the board, the player having the highest score calculated by the total aggregate numbers on the pieces 45 which he has removed from the board is the winner of the game. It will be appreciated that the traveling member and the support therefor may also be used in a variety of other games wherein the successive players are building a 50 score.

What I claim is:

1. A game apparatus comprising a traveling member adapted to be set in motion by a player and means for supporting such member during 55 its movement, the traveling member comprising a shaft, a pair of discs mounted on such shaft in spaced relation, and a hub mounted on the shaft between such discs, and a finger-engaging portion at one end of the shaft adapted to be grasped by the player and twirled to impart motion to the member, the supporting means comprising a base and a rail mounted above and

spaced from the base, the hub adapted to ride upon the upper edge of said rail.

2. A game apparatus comprising a traveling member adapted to be set in motion by a player and means for supporting such member during 5 its movement, the traveling member comprising a shaft, a pair of discs mounted on such shaft in spaced relation, and a hub mounted on the shaft between such discs, and a finger-engaging portion at one end of the shaft adapted to be 10 grasped by the player and twirled to impart motion to the member, the supporting means comprising a base and a rail mounted above and spaced from the base, the hub adapted to ride upon the upper edge of said rail, the base 15 being provided with a plurality of spaced areas marked thereon and numerical designations in said areas to indicate scores when the traveling member comes to rest, the rail having a plurality of spaced recesses on the upper surface thereof 20 and adapted to receive the hub when the member comes to rest.

3. A game apparatus comprising a traveling member adapted to be set in motion by a player and means for supporting such member during 25 its movement, the traveling member comprising a shaft, a pair of discs secured to the shaft in spaced relation, and a hub mounted on the shaft between such discs and being free to rotate 30 thereon, and a thumb turn portion at one end of the shaft adapted to be grasped by the player and twirled to impart motion to the member, the supporting means comprising a base and an inclined rail mounted above and spaced from the base, the hub adapted to ride upon the upper 35 edge of said rail.

4. In a game having a game board provided with a plurality of numbered areas marked thereon, the improvement which comprises a traveling member and an elongated support therefor, the 40 traveling member comprising a shaft, a pair of discs mounted thereon in spaced relation, and a thumb turn portion at one end of the shaft, the support comprising a horizontal rail, a base member and means for mounting the rail in spaced 45 relation to the base member, the portion of the shaft between discs being adapted to ride upon the rail when the shaft is manually set in motion.

5. In a game having a game board provided with a plurality of numbered areas marked thereon, the improvement which comprises a traveling member and an elongated support therefor, the traveling member comprising a shaft adapted to ride upon the elongated support when manually rotated and thumb turn means on the shaft for permitting the starting of rotation, the support comprising a horizontal rail, a base member and means for mounting the rail in spaced relation to the base member, the base portion being provided with a plurality of numbered areas to designate 55 the point at which the traveling member ceases 60 its motion.

CLARENCE A. WATKINS.
